PAPER CUTTING AND DELIVERY MECHANISM FOR WEB CYLINDER LITHOGRAPHING OR PRINTING PRESSES

Walter Harold Smith, Toronto, Ontario, Canada

Application September 16, 1933, Serial No. 689,770

8 Claims. (Cl. 164—68)

My invention relates to improvements in paper cutting and delivery mechanism for web cylinder lithographing or printing presses, and the object of the invention is to devise a device by which 5 paper web of any desired weight may be cut at great speed and controlled after cutting so that a perfect vertical pile may be formed of the severed sheets without adjustment being necessary on account of the varying weight or thickness of the stack being printed and cut, in which 10 the web is fed to the knife by changing the normal path of the web and compelling it to assume a direction of travel in a straight line contrary to its normal curve, in which the cutter may be 15 adjusted while the machine is running either to advance or retard the cut while the machine is in motion to vary the cut with relation to the print, in which means are provided for accelerating the travel of the severed sheet to advance 20 it in relation to the advancing web to move it out of the path of such web before the next sheet is severed, and in which means are provided for preventing the web following the rotary cutter 25 owing to the upward displacement of air caused by the high speed of the revolving rotary cutter or owing sometimes to static electricity which is frequently present in printing presses and preventing the proper delivery of the cut sheet, and it consists essentially of the arrangement 30 and construction of parts as hereinafter more particularly explained.

Fig. 1 is a plan view of my cutting and delivery mechanism carried by the rear end of the main frame of the press.

Fig. 2 is a side elevation of the mechanism illustrated in Fig. 1.

Fig. 3 is a sectional view on line 3—3 Fig. 1.

Fig. 4 is a detail elevation of a portion of the opposite side of the machine shown in Fig. 2.

Fig. 5 is a sectional view through the rotary cutter and adjacent parts and showing the compressed air discharge nozzle in the cutter.

Fig. 6 is a front elevation of a portion of the rotary cutter, the upper portion of part thereof being in section.

Fig. 7 is a sectional view on line 7—7 of Fig. 6.

Fig. 8 is a front elevation of the parts illustrated in Fig. 6.

In the drawings like letters of reference indicate corresponding parts in each figure.

1 and 2 are the side portions of the main frame of the cylinder press, each portion 1 and 2 carrying a bearing standard 3 in which are journaled the conveyor roller 4 and conveyor wheel shaft 5 carrying the conveyor wheels 5^x, the shaft

being mounted in movable bearing blocks 6 held in the standards 3 so that they are carried by gravity onto the web 7 as it passes over the conveyor roller 4. 8 are standards in which is journaled the cutter shaft 9 upon which the rotary cutter 10 is mounted to revolve therewith. The cutter shaft 9 is driven from any suitable power, not shown.

10^a is a stationary ledger blade mounted between the side members 1 and 2 so as to coact with the knife 10^x of the rotary cutter 10. 11 is a plate which extends between the periphery of the conveyor roller 4 and the cutting edge of the ledger blade 10^a, the opposite edge of the plate 11 being very closely adjacent to the periphery of the conveyor roller 4 being slightly up-turned at the periphery of the roller as shown so as to strip off the web therefrom as it travels forward. The plate 11 is suitably mounted in a stationary position such as upon the cross rod 12 by the brackets 13.

14 is a feed roller which is also mounted in the bearing standards 3, the periphery contacted by the upper surface of the web is driven by such web as it passes around the conveyor roller 4 opposite the point where the plate 11 strips the web from the roller 4 and thereby aids in performing such stripping operation and forcing the paper web out of its normal path of travel onto the surface of the plate 11 so that, as it travels thereover, it will have a tendency to cling to such surface and hold the paper or other material absolutely flat as it travels to the cutting point so that the length of paper fed to the cutter after each cutting operation will be exactly the same and will have no tendency to be slightly altered by any looseness in the set of the paper during this part of the conveying operation.

It will thus be seen that by changing the normal path of the web and compelling it to assume a path of travel in a straight line contrary to its normal curve and as it travels in its normal path, is definitely forced onward by the roller 4 and wheels 5 and will cling to the surface of the plate 11 in a straight line until the edge of the blade of the rotary cutter engages therewith. The curved edge 11^x of the plate 11 engages the roller 4 and strips the web therefrom, the rotation of the roller 4 forcing the web forward and into contact with the plate 11 as the web passes over the upper surface thereof. The engagement of the blade with the paper will serve to momentarily stop the forward travel of the paper web at that point and, as the feed

of the roller 4 is continuous, there will be a slight tendency for the paper to buckle upward, the amount of buckle depending upon the weight of the paper fed to the cutting blade. If the paper is very light such as an onion skin paper, there will be only a tendency to buckle slightly adjacent to the blade of the rotary cutter and as the weight of the paper used increases the extent of the buckling will increase rearwardly so that in stiff paper or card board the buckle will take somewhat the form illustrated by dotted lines A in Fig. 3.

After the sheet is severed each sheet must be individually conveyed away from the cutting point to the point of deposit and for this purpose I provide an endless conveyor 15 mounted, at one end, upon a driven drum shaft 16 provided, at its end, with a small pulley 17 driven from the pulley 18 secured to the conveyor roller 4 through the belt 19 connecting the pulleys 17 and 18 together. By this means the conveyor 15 will be driven at a very much accelerated speed to the speed of the conveyor roller 4 and will, therefore, serve to carry the sheets when cut rearwardly at a very much higher speed than the speed of travel of the web 7.

In order to counteract upward lift upon the stack as it advances past the rear side of the rotary cutter, I provide a duct 9^x extending through the shaft 9 leading, at its inner end, into a cylindrical chamber 9° from which extends tangential discharge nozzles 9¹ which discharge compressed air at the rear of the cutting blade 10^x. The discharge is timed by a timing valve 35 which I will now describe.

The outer end of the shaft 9 is plugged as indicated at 58 (see Fig. 6). 59 is a compressed air inlet formed in a bearing 60 in which the plugged end of the shaft 9 is journaled. 61 is a cut-off chamber communicating on one side with the bore of the journal 60 and on the other side with the inlet 59. The duct 9^x is provided with a port 62 which registers with the open side of the cut-off chamber 61 during approximately 80° of the revolution of the shaft 9 so as to feed compressed air to the nozzles 9¹ to direct it against the web as the nozzles pass from the dotted line position to the full line position shown in Fig. 5 forcing the paper web downward towards the dotted position shown in this figure carrying it out of the influence of the upward pull of the revolving cutter until acted upon by the compressed air jets of the pipe 20. By this means it will be seen that a blow is directed in a given path at a predetermined time to blow the sheet forcibly away from the cutter and onto the accelerated travelling delivering means.

In order to ensure that the sheets, immediately after they are cut, engage at their leading edge with the surface of the conveyor 15, I provide a transverse air pipe 20 which is suitably perforated to provide a series of air jets as indicated at 21 which blow upon the upper face of the cut sheet so as to immediately force it into close frictional contact with the surface of the conveyor 15 so that it immediately engages therewith and is carried rapidly rearward. As the cut sheet is carried rearward by the conveyor 15, it is engaged by the idler discs 22 which are mounted in arms 23 carried by a cross rod 24 mounted in standard brackets 25 forming part of the main brackets 26 extending rearward from the side portions 1 and 2 of the frame of the press.

27 and 28 are the side walls of a sheet re-

ceiving receptacle, 29 being the bottom which is adjustably mounted as indicated at 30, mechanism being provided to convey the bottom downward as the pile of paper sheets build up within the receptacle. This mechanism is not shown as it forms no part of the present invention. The side walls 27 and 28 are supported in any suitable manner such as by the hangers 31 carried by a cross rod 32 mounted in the brackets 26.

33 are vertical bars secured to a cross bar 34, the upper end of the bar projecting upward adjacent the periphery of the forward roller 16^x of the conveyor 15 at a height to permit the free passage of the cut sheet thereover. At the opposite or rear side of the sheets receiver, I provide depending bars 35 preferably mounted at their upper end on a rod 36 mounted, at its ends, in the brackets 26, such bars extending above the path of travel of the cut sheet. When the cut sheet is impelled forward at a high rate of speed it passes into the sheet receiver striking the bars 35 at its forward edge and has then a tendency to rebound back so as not to properly enter the receiver. In order to obviate this, I provide a series of fingers 37 mounted, at their rear end, in a rocking shaft 38 which is mounted in the brackets 26 and provided, at its ends, with arms 39 and 40, the arm 39 being connected by a link 41 to a lever 42 pivotally mounted at 43 and carrying a cam roller 44 journaled thereon.

45 is a cam which is secured to the end of the cutter shaft 9 so as to revolve therewith, the arm 42 being spring held rearwardly by the spring 46. It will thus be seen that as the cutter shaft 9 revolves to rotate the cutter it also, by means of the cam 45, imparts a rocking movement to the lever 42 and through the link 41 to the arm 39 so as to rock the shaft 38 and carry the fingers 37 alternately up and down, to and from the dotted position illustrated in Fig. 3 so that as each sheet is fed into the receiver and engages the bars 35 the fingers 37 are swung downward against such sheet knocking it directly downward onto the top of the pile, any tendency to rebound being then taken by the bars 33 thereby holding each sheet definitely in position to form a perfectly vertical pile.

In order to advance or retard the cutting edge of the knife 10^x which is driven from the conveyor roller 4 through the gears 47, 48, 49 and 50, the gear 47 is secured to the feed roller 4 and the gear 50 to the cutter shaft 9. The gears 48 and 49 are idlers intermeshing together and with the gears 47 and 50. The idler gears 48 and 49 are mounted on studs 48^x and 49^x mounted in a link 55. 52 is a link connecting the stud 49^x with the cutter shaft 9. 53 is an arm secured to the stud end 4^x of the feed roller 4 and through the opposite end of which the stud 48^x extends. 54 is a worm quadrant formed integral with the arm 53 and 55 is a worm meshing therewith and secured to a spindle 56 journaled in suitable bearings and operated by a hand wheel 57.

By rotating the hand wheel the parts may be adjusted to and from a dotted position such as that indicated in the drawings to adjust the cutting edge of the cutting knife circumferentially to advance or retard the cut at any time during the operation of the machine.

From this description it will be seen that I have devised a machine by which webs of varying thickness one with the other may be accurately fed to the cutter so that each sheet is cut exactly the same length and when cut conveyed to the sheet receiver and received so that the rebound

of the sheet discharged at high speed against the rear wall of the receiver will be eliminated, each sheet being carried vertically downward at the point of rebound onto the top of the vertical pile instead of being carried back by such rebound to engage the next delivered sheet and consequently ensuring of the building of a pile, the opposite walls of which are parallel and preferably vertical without interference with the sheets passing from the point of discharge.

What I claim as my invention is:

1. In a cutting and delivery mechanism for a cylinder press, the combination with the rotary cutter and the feed roller, of gears secured to the cutter and feed roller shafts, intermeshing idler gears meshing with the gears of the cutter and feed roller, a link connection swung upon the cutter and feed roller shafts on which the idlers are mounted, and a manually operable worm gear for adjusting the position of the links around the cutter and feed roller shafts.

2. In a cutting and delivery mechanism for cylinder presses, the combination with a conveyor roller over which the paper web is fed to pass downward, of a substantially horizontal plate extending from the periphery of the roller adjacent its horizontal diameter, and an idler roller contacting with the web and spaced from the conveyor roller and plate a distance sufficient to hold the web closely adjacent to both roller and plate.

3. In a cutting and delivery mechanism for cylinder presses, the combination with a revolving cutter, means for feeding a freshly printed web in a horizontal direction towards the cutter, a sheet receiver, means for engaging the unprinted face of the web for conveying each sheet from the cutting point to the receiver at an accelerated speed, and means opposing and having no mechanical contact with the freshly printed face of the web for pressing the web into contact with the conveying means.

4. A device for severing a freshly printed web into sheets comprising in combination a stationary blade over which the sheet passes printed side up, a revolving cutter coacting with the stationary blade to sever the sheet and force the cut edge of

the severed sheet down and away from the stationary blade positively and out of the path of the on-coming cut end of the travelling web and a travelling conveyor travelling at a greater speed than the web and on which the sheet is carried, and means for pneumatically holding the sheets in contact with the conveyor.

5. In a cutting and delivery mechanism for cylinder presses, the combination with a rotary cutter and feed roller shafts, intermeshing idler gears meshing with the gears of the cutter and feed roller, a link connection swung upon the cutter and feed roller shafts on which the idlers are mounted, and manually controlled means for adjusting the position of the links around the cutter and feed roller shafts.

6. In a cutting and delivery mechanism for cylinder presses, the combination with a web feeding mechanism, of a rotary cutter coacting with the feeding mechanism to cut the web into sheets, a compressed air duct leading axially through the body of the cutter, nozzles leading tangentially from the duct to the periphery of the cutter, and means for supplying air to the duct and nozzles after the cutting of each sheet and during the upward travel only of the cutter.

7. In a cutting and delivery mechanism for cylinder presses, the combination with the press and a rotatable cutter to which the printed web is fed printed side up, of a high speed horizontal conveyor spaced below the cutting level and onto which the sheets as they are cut are dropped successively, and means having no mechanical contact with the freshly printed face of the sheet for pressing the opposite or unprinted face of the sheets into contact with the conveying means.

8. In a cutting and delivery mechanism for cylinder presses, the combination with a conveyor roll over which the web is adapted to travel longitudinally, of a rotary cutter located above the path of travel of the web and coacting with the ledger blade to cut the web into sheets, and means incorporated in the structure of the cutter for directing compressed air against the severed sheet adjacent its following edge as such edge passes adjacent the rear of the cutter.

WALTER HAROLD SMITH.
